LUGGAGE LOCK

Joseph Pelavin, Brooklyn, and Julius Sheiman, North Woodmere, N.Y., assignors to Lark Luggage Corp., New York, N.Y., a corporation of New York

Filed Sept. 15, 1965, Ser. No. 87,016

Term of patent 14 years

(Cl. D50—7)

FIG. 1 is a front perspective view of a luggage lock showing our new design embodied in a luggage case, the luggage case being shown in broken lines and forming no part of the present invention;

FIG. 2 is a top plan view thereof, on an enlarged scale, with only a fragmentary portion of the case being shown;

FIG. 3 is a side elevational view thereof, on an enlarged scale, with only a fragmentary portion of the case being shown;

FIG. 4 is a front elevational view thereof, on an enlarged scale, with only a fragmentary portion of the case being shown; and

FIG. 5 is a front perspective view thereof with the lock shown in an opened position, on an enlarged scale, with only a fragmentary portion of the case being shown.

We claim:

The ornamental design for a luggage lock, as shown and described.
